US0D1012257S

(12) **United States Design Patent** (10) Patent No.: **US D1,012,257 S**
(45) Date of Patent: ** Jan. 23, 2024

(54) **AIR PURIFIER**

- (71) Applicant: **COWAY CO., LTD.**,
Choongcheongnam-do (KR)
- (72) Inventors: **Jungjae Jeon**, Seoul (KR); **Eung Kyu Park**, Seoul (KR); **Ga Hee Kim**, Seoul (KR); **Sumin Shin**, Seoul (KR)
- (73) Assignee: **COWAY CO., LTD.**,
Choongcheongnam-Do (KR)

(**) Term: **15 Years**

(21) Appl. No.: **29/786,075**

(22) Filed: **May 28, 2021**

(30) **Foreign Application Priority Data**

Dec. 1, 2020 (KR) 30-2020-0058768

(57) **CLAIM**

The ornamental design for an air purifier, as shown and described.

DESCRIPTION

FIG. 1 is a front perspective view of an air purifier showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines illustrate portions of the air purifier that form no part of the claimed design.

1 Claim, 7 Drawing Sheets
